Application December 31, 1941, Serial No. 425,146

10 Claims. (Cl. 60—53)

1

This invention relates to systems for controlling the movement of bodies possessing substantial inertia, such as rotatably mounted guns and the like, and it refers more particularly to a system for automatically positioning a gun in accordance with angular data supplied from a remote source such as a fire-control director.

In the past, guns and particularly anti-aircraft guns, have been aimed manually in elevation and in train (azimuth) according to data exhibited by indicators at the gun, such as dials rotated by the receivers of self-synchronous transmission systems over which the data arrived from a remote director. The men aiming the gun in accordance with received data, in such systems, are situated alongside of the gun and hence are subjected to the shock of gun fire while trying to perform the difficult feat of continuously reproducing the received data as closely as possible in aiming angles. Our present system of control overcomes this and other disadvantages of earlier methods of control by rendering the aiming of the gun entirely automatic under the control of the received data without any need for manually setting angles or performing other manual operations at the gun but it permits a quick change to manual operation under abnormal conditions.

In providing a remote control system for an object such as a gun, which has high moments of inertia about its rotational axes, we have invented features which are particularly adapted to prevent the hunting or oscillation about a position of rest to which such objects are subject.

One object of the invention is, therefore, to provide automatic control of the aiming of a gun from a source such as a fire-control director.

Another object of the invention is to provide, for an object possessing substantial inertia, a remote control system which is free from hunting tendencies.

Another object is to employ, as anti-hunting control terms, functions of the data (representing the position of a controlling object) and gun position and particularly time derivatives of the variation of these quantities.

A further object is to provide an indication of the functioning of a system of the above character which is influenced by the degree of positional disagreement of the controller and gun and the rate of change of relative position of these bodies.

Another object is to provide a system of the above character which is fully self-synchronous and free from ambiguity.

2

A further object is to provide in a system of the above character protection against overloading of the driving means, including means for causing delayed or only partial response to suddenly changing data.

A further object is to provide limit stops which prevent overrunning without putting undue strain on the driving means.

Still another object is to provide in an automatic system of the above character suitable switching means for conversion to manual operation.

In the drawings,

Fig. 1 is a schematic diagram of a gun-positioning system embodying one form of the invention.

Fig. 2 is a diagrammatic perspective view of a power limiter adapted for use with the system of Fig. 1.

Fig. 3 is a simplified perspective view of a gun mounted for rotation in train (azimuth) and in elevation, showing certain of the elements of the control system of Fig. 1.

Fig. 4 is a diagrammatic showing of certain details of Fig. 1.

Referring now to Fig. 1, the apparatus units shown at the upper left-hand corner are associated with a gun fire director which may be, for example, of the type described in United States Patent No. 2,065,303, issued to E. W. Chafee et al., December 22, 1936, or which may incorporate certain features disclosed in the co-pending application of one of the present inventors, H. Hull, joint with W. Hartman and R. Goertz, Serial No. 403,618, filed July 23, 1941. The units shown are those concerned with the transmission of the angle of elevation only, it being understood that similar apparatus may be employed for the transmission of angle of train (azimuth) data. Likewise, at the gun, only elevation control elements are illustrated in the figure, a similar arrangement for azimuth positioning being implicit in the disclosure.

Gun elevation is represented in the director by the angular position of shaft 10, connected by gearing to drive the rotors 13 and 14 of Selsyn transmitters 11 and 12, respectively, each of said rotors being excited from a suitable A. C. source. The two rotors 13 and 14 are driven at relatively different speeds, corresponding to the ratio of gears 15 and 16, to provide coarse and fine data transmission channels, as is common practice in fire control data transmission systems, a ratio of 16:1 between the data amplitude of the two channels being often employed. The position of

rotor 13 determines the voltages induced in the three windings of associated stator 17, which voltages are transmitted over three-wire line 17' to three-winding rotor 18 of Selsyn receiver 19, located at the gun. Similarly, the position of rotor 14 determines the voltages induced in the windings of stator 20, which are transmitted over three-wire line 20' to rotor 21 of Selsyn receiver 22, likewise located at the gun. Receivers 19 and 22 are operated as locked rotor devices, sometimes called signal generators since a signal voltage is generated proportional to the displacement of each rotor from the datum position. Rotor 18, for example, is connected to generate a gun position signal by being driven through gearing in correspondence with gun 23, while rotor 21 is similarly driven but at a different rate. The term "synchro transformers" is also applied to devices such as 19 and 22. It is immaterial in the transmitter whether the single-winding element, as shown, or the three-winding element be made the rotor, since only the relative position of the two elements determines the transmitted voltages.

The voltages in the windings of rotor 18 induce an A. C. voltage in stator winding 24, while the voltages in the windings of rotor 21 induce an A. C. voltage in stator winding 25. These two stator voltages, which are both proportional to the positional disagreement of gun 23 and shaft 10, but in a different ratio, are combined in a circuit which supplies an input to amplifier-modulator 50, to be later described, and a voltage limiter 26 is connected across the output circuit of stator 25 for the purpose of shifting control from the fine to the coarse transmission channel when the disagreement of the transmitter and receiver exceeds the range of fine transmission.

When the gun and director are in synchronism, the voltage in stator winding 25 of the fine transmission channel is zero. Displacement of the director elevation shaft (data) by a small angle in one direction results in an A. C. voltage being induced in winding 25 proportional to the displacement and having a phase dependent upon the sense of the displacement. A displacement in the opposite direction results in a reversal of phase of this voltage. A position of stable equilibrium is thus defined. Considering the coarse channel, when the gun and director (data) are in synchronism the voltage across winding 24 is not zero due to an initial or biasing displacement which is given the stator mounting this winding but this initial voltage is balanced out by the voltage from transformer 30, supplied from the common A. C. source and having a resistance-capacity phase adjustment 31 in its input circuit, which voltage is made equal in magnitude but opposite in phase thereto. The coarse as well as the fine channel is therefore in stable equilibrium at this point.

When the gun is positioned 180° away from the synchronous position, i. e., from the angular value of the data, the voltage in winding 25 is zero, but the voltage in winding 24 is reversed in phase and so is of the same phase as the voltage supplied by transformer 30. These two voltages therefore do not annul one another and no equilibrium of the coarse transmission channel results at this point. The purpose of the voltage supplied from transformer 30 is thus seen to be to prevent the occurrence of two positions of stable equilibrium in which the controlled object could otherwise move in synchronism with the controlling object. It will be found upon analysis that any position, other than the synchronous position, at which

zero voltage exists simultaneously in windings 24 and 25 is one of unstable equilibrium for both the fine and coarse channels. This mode of operation is more fully described in the pending U. S. applications of Eric J. Isbister and Francis L. Moseley, Serial No. 304,895, filed November 17, 1939, and of Francis L. Moseley, Eric J. Isbister and H. B. Steinhauser, Ser. No. 382,020, filed March 6, 1941, both assigned to the assignee of the present inventors.

Voltage limiter 26 comprises saturable reactor 27, across which the output of the fine transmission channel is applied, and attenuator 28, the latter being shown for illustration in the form of a T resistance network. The voltage induced by stator 25 across reactor 27 may be adjusted by suitable choice of the characteristics of attenuator 28.

The constants of attenuator 28 and the saturation characteristics of reactor 27 are preferably so chosen that the maximum voltage appearing across reactor 27 is limited to a value which will allow the voltage of stator 24 (of the coarse transmission channel) to take control when the disagreement between gun and data is greater than the range in which the fine transmission gives correct electrical indication. When a ratio of 16:1 between fine and coarse transmission channels is used the shifting of control from one to the other should occur before the disagreement reaches approximately 12 1/4 degrees.

Since the ratio of the fine transmission channel is 16 to 1, the amplitude of the fine alternating potential signal would go through sixteen complete cycles for every 360 degree change in the angle of disagreement between the gun 23 and the director shaft 10. Were the fine transmission channel to solely control the position of the gun, the direction of control exerted thereby would only be correct for one-half cycle to either side of the zero disagreement position. Accordingly, it is necessary to render ineffective the control exerted by the fine transmission signal beyond such limits.

This limitation of the range of control of the fine transmission signal is accomplished in the voltage limiter 26 which operates to prevent the fine alternating potential signal from ever exceeding a predetermined amplitude. This amplitude is so chosen that the sum of both the coarse and fine alternating potential signals is always of the same sign as that of the coarse potential signal. In this manner when there is only slight disagreement between the positions of the gun and the director shaft, the fine transmission potential signal exerts the preponderant control, since the coarse transmission potential signal has not as yet built up to a substantial magnitude. High accuracy of following is thus obtained under these conditions. However, when the disagreement between the gun position and the director shaft position is substantial, the coarse potential signal has built up to a value which is greater than the limited value of the fine potential signal. Thus, correct direction of control is obtained for all ranges of disagreement, while highly accurate control is obtained when the gun and director shaft are in substantial agreement, which latter condition is the normal operating condition.

The circuits so far described provide means for obtaining a signal voltage indicating disagreement of the gun position and the transmitted data and closely proportional to such dis-

agreement, at least over a limited range, the phase of the voltage indicating the sense of the error. This voltage is applied across resistances 32 and 33, which form a voltage divider.

Means for obtaining auxiliary signals proportional to other quantities, which we combine with the disagreement or error signal, will be described later.

The voltage drop across resistance 33 is applied to input resistances 42 and 43 of balanced modulator 50 in a mixer circuit which may be traced from one terminal of resistance 33 by way of lead 34 to the outer terminal of resistance 43 and from the other terminal of resistance 33 by way of resistances 35, 36, 37, 38, 40 and lead 41 to the outer terminal of resistance 42.

Modulator 50 is A. C. operated and comprises two triode or other multi-electrode vacuum tube units in a push-pull circuit, in which a bias is supplied to both units by the drop, due to plate current, across resistance 51. The input to this modulator is a combination of A. C. and D. C. signal voltages from the mixer circuit and the output is an A. C. voltage, having components which, in phase, and magnitude, represent the polarity or phase and magnitude of the input signals.

The preferred form of modulator shown in Fig. 1 uses A. C. on the plates for converting the D. C. signal voltages to an A. C. voltage, the magnitude of which is proportional to the magnitude of the D. C. input, and the phase of which is determined by the polarity of the D. C.

A modulator may alternatively be used which is supplied with D. C. on the plates and obtains the conversion to A. C. by the use of fixed A. C. bias between cathodes and grids, it being immaterial whether the constant A. C. is supplied in the grid or plate circuit of the tubes. The output of modulator 50 is passed by transformer 52 to balanced amplifier 53 which supplies an amplified A. C. signal through transformer 54 to one stator winding 56 of two-phase motor 55, the other winding 57 of which is supplied from the common A. C. supply of the system. Condenser 58 is for phase adjustment or phase splitting.

Motor 55, through bevel gears 59, crank 60, push-rod 61 and power limiter 62, positions stroke rod 63 of a Vickers hydraulic variable speed gear 64 comprising a pump or "A" end 65, a hydraulic motor or "B" end 66, and an electric driving motor 67. The Vickers gear is well known to persons skilled in the art and is described in detail in United States Patent No. 2,189,823, issued February 13, 1940, in the names of H. F. Vickers and N. B. Frost and entitled Apparatus for controlling the movement of heavy masses. The speed of the motor or "B" end of this gear, neglecting leakage, is proportional to the setting of the stroke rod 63 which determines the angle of tilt of the pump cylinder block and hence the stroke of the pistons. Since the motor or "B" end 66 directly actuates the gun 23, the setting of the stroke rod 63 is proportional to the angular rate of rotation of gun 23. A sump for the operating fluid used in this gear, which is generally oil, is shown at 68 and a replenishing pump driven by motor 67 is shown at 69. In operation, fluid circulated by pump 65 causes rotation of motor 66 and of gun 23 driven therefrom through gears 81.

Returning now to the means for generating the different voltages which control the setting of the stroke rod of the Vickers gear, the means for generating a signal proportional to disagreement

of the gun position and datum have been described. In addition to this primary signal, as noted, auxiliary signals are employed. One of these auxiliary signals is proportional to the rate of change of the transmitted elevation data, that is, to the rate of change of position or speed of turning of shaft 10 and rotors 13 and 14. This signal is supplied as a D. C. voltage by generator 70, shown as having a field excited by a suitable D. C. source. It may be preferable in some instances to employ permanent magnet excited generators for those described herein as D. C. excited. Generator 70 is driven by a "chaser" motor controlled by the elevation data shaft 10, here illustrated as reversible two-phase induction motor 71 having stator windings 72a and 72b, the former winding being constantly excited from a suitable A. C. source. Motor 71 is constrained to follow the motion of shaft 10 through gearing and a follow-up device 73, comprising roller contact 74 and cooperative contact segments 75 and 76 separated by insulating "dead spot" 77. The phase of the current in winding 72b, which is shifted relative to that in windings 72a by condenser 78, has opposite values depending on which contact segment roller 74 rests on, thereby providing reversible operation of the motor. The output voltage of generator 70, which is proportional to the speed at which the armature is rotated, is applied across resistor 37 and is filtered by the resistance-capacity network comprising resistance 38 and condenser 79 to smooth out or eliminate peaks due to sudden changes of the rate of change of the data, corresponding to acceleration of shaft 10.

The next signal, means for obtaining which will be described, is one proportional to the speed of rotation of the gun in elevation. This is obtained as a D. C. voltage from generator 80 having a permanent magnet field or one excited from a suitable D. C. source. Generator 80 is driven by gearing, including gears 81, from gun 23 and applies a voltage proportional to the speed of rotation of the gun across a potential divider comprising resistances 39 and 39' connected in series. Resistance 39 has a variable contact 45 by means of which the magnitude of the gun velocity signal to be utilized can be adjusted.

Two other signals are employed, one, a D. C. signal proportional to the position of stroke rod 63 of the variable speed gear and the other, a D. C. signal proportional to the rate of change of position of this rod. If there were no leakage in the hydraulic transmission and no lost motion in the gun drive, the position of the stroke rod would be strictly proportional to the speed of rotation of the gun. In practice, however, there is a slight lag in the response of the gun to a change of position of the stroke rod, and while at constant velocity either the stroke rod position or the gun velocity signal obtained from generator 80 would be sufficient, in order to care for all transient conditions which might encourage instability, we prefer to use both signals and, in addition, a signal derived from the stroke rod signal which is substantially proportional to the angular acceleration of the gun.

A variable coupling transformer 90 having a rotatable winding 91 excited from a suitable A. C. source through multi-winding transformer 92 and rotated by motor 55, through gearing 59, in positional correspondence with stroke rod 63, is provided with a pair of stator windings 93 and 94 in each of which an A. C. voltage is induced corresponding to the position of rotor 91, the voltages

in windings 93 and 94 being of opposite phase. In series with each of these two windings there is connected one of secondary windings 95 and 96 of transformer 92 to supply voltages of constant phase.

Windings 93 and 94 feed phase sensitive rectifier circuits including bridge type rectifiers 97 and 98 respectively. The D. C. output voltage of each rectifier is proportional to the A. C. input, and the polarity of the output is determined by the phase relation of the input A. C. voltage from 93 and 94 to that of the voltage supplied by winding 95 or 96 as the case may be. The outputs of rectifiers 97 and 98 are serially combined and applied to low pass filter 100 across center-tapped input resistor 99. The D. C. output of filter 100, from which A. C. ripple has been substantially removed, is applied across tapped resistance 40 serving as a potential divider.

Also driven from motor 55 through gearing 59 and 101 is stroke rate generator 102 having a field excited from a suitable D. C. source. The armature of generator 102 being moved in positional correspondence with stroke rod 63, the generated D. C. voltage is proportional to the rate of change of stroke and therefore is substantially proportional to the acceleration of the gun, since the stroke position is proportional to the velocity of the gun, as previously brought out. This voltage is applied to resistances 35 and 35' connected in series as a potential divider.

To summarize, there are applied to the input of modulator 58 to control the operation of gun driving means, an A. C. error signal, and D. C. signals representing director shaft velocity or rate of change of data, gun velocity, stroke rod position and stroke rod velocity, the two last named signals representing substantially gun velocity and gun acceleration respectively. The purpose of the auxiliary D. C. signals is to overcome the effect of the inertia and other characteristics of the controlling and controlled objects, and of the means connecting these objects, in tending to promote overshooting and hunting of the controlled object (gun) relative to the angular positions, this object should assume in response to the data. For a further discussion of the use of time derivatives of the error signal to provide anti-hunt characteristics in a remote control system, reference may be had to U. S. Patent No. 2,233,415, dated March 4, 1941, to H. L. Hull, one of the present inventors.

We have described arrangements for causing the gun driving means to be actuated in a preferred manner. The gun, however, being possessed of high inertia, cannot respond instantly to change of transmitted data and there will consequently be periods when the data will not be accurately reproduced in aiming angles. The seriousness of any such discrepancy depends to a certain extent upon whether the gun position is approaching or moving away from the datum position, that is, upon the relative rate of change of gun position and datum. Accordingly, we supply an indication, somewhat in the nature of a figure of merit of the system, which combines the error of gun following with the difference of the rates of change of gun position and of datum, the latter term representing the relative rate of change of the two angles.

Transformer 103 (Fig. 1) is connected to receive the voltage across resistances 32 and 33 which is proportional to the error in following. This transformer has two secondary or output windings and the voltage induced in each is com-

bined with a voltage of constant phase derived from the Selsyn exciting source through transformer 103' to obtain a phase-sensitive device as described in connection with the circuit including transformers 90 and 92. Rectification of these voltages is accomplished in bridge type rectifiers 104 and 104' which may be of the dry disc variety connected in a push-pull circuit. A D. C. voltage is thus obtained across center-tapped resistance 105 which is combined in series with a selected portion of the voltage across resistances 37 and 38 and applied to meter 106, preferably of the high resistance or voltmeter type. The adjustment of the voltage derived from the drop across resistance 37, which drop, as has been pointed out, is proportional to the rate of change of transmitted data, is made by means of variable contact 37' while the adjustment of the voltage proportional to rate of change of gun position is made by sliding contact 38', these resistance adjustments determining the degree to which the lag error indication is modified by the relative rate of change of gun position and data.

The purpose of this arrangement is to cause the meter to give an indication which is a combination of the error and the rate of change of the error. In addition to showing the fidelity of automatic operation it enables an operator to anticipate the approach of the gun to the correct position during manual operation and to govern his control accordingly.

It will be apparent from the above description that a combination of three signals are applied to the meter: a voltage proportional to the error in following, a voltage proportional to gun speed; and a voltage proportional to rate of change of the angle transmitted from the director. The resistances across which the signal voltage drops are taken are so adjusted that when the gun 23 and director shaft 10 are rotating at the same speed the two speed voltages generated by generators 70 and 80 are equal and opposite and therefore annul one another. When the gun or the director shaft changes speed, however, a difference in voltage is produced which represents the speed of approach or separation of the gun and datum angle. This resultant signal, when added to the error signal in the proper relationship, causes the meter to "anticipate" future error. The degree of "anticipation" provided is adjustable by means of contacts 37' and 38' and by moving these contacts to adjacent ends of the resistances with which they cooperate, meter 106 may be caused to indicate lag only.

We have found that it is highly desirable to provide certain safety devices in connection with the Vickers gear as used in our control system to prevent excessive hydraulic pressures being built up and to prevent excessive power demands on the pump driving means 67. The location of these devices in the driving system is shown in Fig. 4 by the block 108, details being shown in Fig. 4.

One safety device is a pair of spring loaded pressure relief valves. Normally, outlet pipes 107 of pump 65 are in connection with corresponding pipes 107' leading to hydraulic motor 66, and the pressure built up by pump 65 must therefore be sufficient to overcome the entire load on motor 66. Under certain conditions, excessive pressures might thus be built up. To prevent this, relief valves 111' and 111 are provided. As seen in Fig. 4, valve 111', for example, comprises a ball 112 normally pressed against a spherical or frusto-conical seat by spring 113 thus closing

pipe 114 leading to one of pipes 107. When the pressure of spring 113 is overcome by pressure in pipe 114, ball 112 lifts and provides a by-pass to the other of pipes 107. Ball 115 of valve 111 is actuated by oil pressure in the reverse direction and would similarly provide a passage between pipes 107 should the direction of fluid flow be reversed from that indicated in Fig. 4 and the pressure built up in the reverse direction between pipes 107 exceed the maximum allowable pressure. Actuation of the valves interconnects pipes 107 and allows circulation of oil at maximum allowable pressure by pump 65 without corresponding rotation of motor 66.

Several conditions may occur under which the by-passing of pipes 107 by valves 111' and 111 is essential to the operation of the system as, for example, when a shift to manual operation is made by operating transfer valve 130, and when limit stop valves 140 and 140' are actuated, as will be later referred to.

Another safety feature is provided in power limiter 62, shown in detail more particularly in Fig. 2. This device operates to prevent excessive power demands on the gun driving means, including the hydraulic transmission, under abnormal conditions as, for example, when stroke rod 63 is suddenly given a large displacement. Such a sudden and large stroke rod displacement calls for a correspondingly sudden and large change of speed of motor 66 and, where a high inertia load such as gun 23 must be suddenly accelerated, tends to cause a severe strain on the driving means. To prevent this, we provide means for limiting the maximum stroke of the pistons of pump 65 responsive to output pressure of the pump, and since the power delivered by the pump is proportional to the product of stroke and pressure, we are thus enabled to limit the maximum power which can be delivered at any stroke setting and can select a preferred law of variation of this maximum pressure with stroke setting signal. Such a law may be, of example, constant power pump output regardless of the input to motor 67.

If motor 67 driving pump 65 should be loaded so as to develop pressures equal to the relief valve settings, as, for example, if pipes 107 should be completely blocked, the stroke of the pump may, by our power limiter, be reduced to a value such that the power dissipated by the pump is well below the normally available maximum power. It is thus possible even to block rotation of the gun, as is desirable under conditions to be described, and maintain maximum pressures in pipes 107 without excessive power consumption or excessive heating of the equipment.

Stroke rod 63 (Fig. 2) is shown as operated by rotation of a cruciform member 120 pivotally mounted on shaft 122, pivoted to datum at 121. The angular position of member 120 in normal operation is determined by the setting of push rod 61, the motion of which is communicated to shaft 122 through crank arm 123. A second crank arm 124 is also rigidly mounted on shaft 122. Arm 124 mounts a pin or stud 125 which is normally oppositely engaged by jaws 126 and 127 mounted for independent free rotation about shaft 122, the two jaws being oppositely pressed against stud 125 by spring 128. Also oppositely engaged by jaws 126 and 127 is upwardly extending stud 129 mounted on the arm of member 120 opposite to that with which rod 63 connects. This arrangement of a pair of studs engaged by spring pressed jaws forms a coupling for trans-

mitting motion from arm 124 to cruciform member 120 (or in the opposite direction) when the resistance to such motion is insufficient to overcome the pressure of spring 128 and open jaws 126 and 127, which is the case during normal actuation of rod 63.

For modifying the setting of rod 63 (shown in Fig. 2 in the position for zero stroke) to care for abnormal conditions, we provide two like cylinders 130 and 130' connected by pipes 110 and 110', respectively, to pump outlet pipes 107. A piston 131 is movable in cylinder 130 under the influence of fluid pressure transmitted by way of pipe 110 against the resistance of a compound spring comprising a stiff spring 132 and a concentric weak spring 132'. Small displacements of piston 131 are controlled by spring 132' whereas both springs 132 and 132' act in controlling larger displacements. Piston rod 133 extends from piston 131 through the cylinder head and is normally positioned with clearance between its outer end and one of the two opposite lateral extensions of member 120. Cylinder 130' contains a piston and spring similar to those described in connection with cylinder 130. From the piston in cylinder 130' extends piston rod 133' ending a slight distance from the other lateral extension of member 120. Member 120 is not engaged by either of piston rods 133 or 133' until a relative displacement occurs which is greater than the displacement of member 120 during normal operation.

Should, however, excessive pressure be built up in cylinder 130, for example, piston 131 and rod 133 will be moved, at first against the relatively slight opposition of spring 132' and later against the greater opposition of springs 132 and 132' in combination. If this occurs at a time of large stroke rod displacement (calling for high acceleration and velocity of the B-end) contact is made with member 120, stopping further stroke rod movement. Further motion of rod 133 will also cause rotation of this member in a clockwise direction resulting in movement of stroke rod 63 in a direction to shorten the stroke of pump 65 and thus limit the developed power. In moving rod 63, piston 131 does not have to move rod 61 and thereby operate against the high resistance of all the elements connected to that rod, since the resistance of spring 128 is made relatively low and therefore allows stud 129 to move jaws 126 and 127 apart as member 120 is rotated against the sole resistance of the spring without displacing arm 124 and rod 61.

In a manner similar to that described, increasing pressure in pipe 110' causes piston rod 133' eventually to engage member 120 and rotate said member in a counter-clockwise direction, thereby to limit the stroke of pump 65 when operating in the reverse direction. By adjustment of clearances and suitably proportioning the relative strength of springs 132 and 132' and of the corresponding springs in cylinder 130', a preferred law of variation of maximum power may be attained. Furthermore, a change from one law to another may be had corresponding to the effective change of spring strength brought into play. Control automatically reverts to stroke motor 55 when abnormal conditions are abated.

A further safety feature is provided in the form of limit stops preventing overrunning of the gun in elevation, only, no azimuth stops for gun operation being normally necessary or desirable. These stops cooperate with power limiter 62 and relief valves 111' and 111 to bring the gun to

stand still without imposing undue strain on the driving means or mount.

A pin 135 (Fig. 3) on gun elevation gear sector 164 engages a lever 136, pivoted on the gun mount, when the gun reaches the lower limit of its travel about horizontal trunnion 150. Lever 136 operates rod 137 which in turn operates valve rod 138 (Fig. 4) through a crank or other suitable connection. Rod 138 mounts valve piston 139, slidable in valve cylinder 144, of the valve 140, which cooperates with a port 141 connecting with pipe 142 leading to transfer valve 180, thus normally providing a free connection between corresponding pipes 107 and 107' by way of valves 140 and 180. When stop pin 135 engages lever 136, piston 139 is moved to the left and gradually obstructs port 141, it being seen that piston 139 is provided with a chamfered edge for obtaining a gradual throttling action. Gradual obstruction of port 141 causes an increasing pressure to be built up in one of pipes 107 which eventually brings power limiter 62 into play to prevent excessive demands on pump 65 and motor 67. With port 141 completely blocked, flow of fluid from the hydraulic motor 66, through the lower of pipes 107, through pipe 142 and port 141 and the lower one of pipes 107 back to the pump 65 is prevented and motion of the gun in elevation ceases. The setting of relief valve 111' is normally such that when port 141 is completely closed, this valve operates to by-pass fluid between pipes 107.

When the elevation data is such as to require the gun to reverse its direction, that is, to increase its elevation, the direction of fluid flow will tend also to reverse and it is then necessary to provide a path for a reversed circulation of oil, otherwise blocked by piston 139. Spring loaded check valve 145, which is actuated in response to such reverse flow, under this condition by-passes valve 140 until such time as lever 136 is no longer engaged with pin 135 and piston 139 returns to its normal position in response to the pressure of spring 143.

A second pin (not shown) or gear sector 164 actuates valve 140' to prevent overrunning of the gun beyond the highest desired elevation angle. The operation of valve 140' is in all respects similar to that of valve 140 except that the lever operated by rod 137' is reversed, and as primed reference numerals in Fig. 4 relate members of this valve to like members of valve 140, its operation will be readily understood without further description or explanation.

In Fig. 3 the manner of mounting certain of the control and indicating units at the gun is illustrated, as well as the rotatable mounting of the gun itself. Gun 23 is pivoted about horizontal trunnion 150 for rotation in elevation while platform 151 on which the assembly of gun and associated units is supported is pivoted about a vertical pin (not shown) for rotation in azimuth.

The azimuth drive is mounted on a hollow column 152 supported from platform 151. The hydraulic motor or "B" end of the azimuth variable speed gear is connected to drive a vertical shaft within this column mounting a pinion 154 meshing with a stationary azimuth gear 155. The "A" ends of both azimuth and elevation drives are enclosed in a housing 156 which may also enclose the stroke setting motors, auxiliary signal generators and associated equipment. Mounted at the top of column 152 is an azimuth indicator 157, seen in rear aspect.

The elevation driving motor 66 (Fig. 1) is mounted in a housing 158 on column 159, sup-

ported from the gun mount, and is connected to drive a worm or pinion (not seen in Fig. 3) meshing with elevation gear sector 164. Elevation indicator 163 is mounted at the top of column 159 and comprises a Selsyn receiver 161 (Fig. 1) operated as a free rotor device having a stator winding 168 excited from the common A. C. supply and a rotor 169 on the shaft of which is mounted indicator dial 170.

10 The windings of rotor 169 are connected across transmission line 17' in parallel with the windings of signal generator rotor 18. The position of dial 170 therefore indicates the transmitted data and provides a check on the operation of 15 the automatic positioning equipment. The indication of this dial also is used in connection with operating means such as handwheels 164' provided for manual aiming of the gun. Similar handwheels 162 are provided for manual aiming 20 of the gun in azimuth in accordance with data shown by indicator 157.

The shift from automatic to manual operation in elevation is made by means of transfer valve 180 (Fig. 4) having operating knob 181 on valve stem 182 for displacing pistons 183, 184 and 185 in cylinder 186. Normally, for automatic operation, pipe 142 communicates with the lower of pipes 107' by way of the space between pistons 184 and 185 and similarly, pipe 142' communicates with upper pipe 107' by way of the space between pistons 183 and 184. This is the condition shown in the figure. For manual operation, knob 181 is pulled out to a position (determined by a stop, not shown) such that piston 185 35 completely blocks the opening of pipe 142 and such that the space between pistons 184 and 185 permits unimpeded flow between the two pipes 107'. Thus, fluid displaced by motor 66 during 40 operation of handwheels 164' can circulate freely without passing through pump 65.

The blocking of pipe 142 brings into play power limiter 62 as in the case of the operation of the limit stops which limits the load imposed on pump 65 and motor 67 but allows these units to continue to operate so that a switch back to automatic operation can be quickly made at any time. The pressure developed may be sufficient to cause the operation of one of relief valves 111' or 111 but the power delivered by the pump will still be kept by limiter 62 well below the permissible maximum. It is to be understood that in order to maintain the hydraulic transmission in operative condition at all times, accessory devices may be necessary such as drainage pipes, etc., as is understood by those skilled in the art.

Briefly reviewing the functions of the apparatus shown in Fig. 4, a pressure is built up between pipes 107 by pump 65 in one direction or the other, depending upon the phase of the composite potential output signal of balanced amplifier 53. The direction of pressure and resulting fluid flow indicated in Fig. 4 is that which would be caused by a signal voltage requiring a decrease in the elevational position of the gun. 60 Under these assumed conditions the direction of flow will normally be from pump 65 through the upper of pipes 107, through limit stop valve 140', through pipe 142', through transfer valve 180, and through the upper of pipes 107' to the hydraulic motor 66. In its return path from the hydraulic motor the fluid will traverse the lower of pipes 107', transfer valve 180, pipe 142, limit stop valve 140, and the lower of pipes 107 back to pump 65.

65 The transfer valve 180 is provided in order to

completely cut off the hydraulic motor 66 from the fluid pressure supplied by pump 65, in case manual control of the gun is desired. The transfer valve 180 accomplishes this simply by blocking the path of oil from pipes 142 and 142' to pipes 107, respectively, and simultaneously providing an inter-connecting channel between pipes 107.

Limit stops 140 and 140' are provided to also interrupt the supply of fluid to motor 66 in case the gun 23 should reach predetermined limits of operation. Thus, when the gun has reached its lower limit of operation, piston 139 of limit stop valve 140 is automatically displaced by the motion of the gun to such a position that it blocks port 141, thus interrupting the supply of fluid to the motor. While the elevation data remains such as to require that the gun be lowered in elevation, the direction of fluid pressure will remain the same and will tend to cause current flow as indicated in Fig. 4. However, fluid flow from the hydraulic motor will be prevented by valve 140 and hence valve 112 will open to by-pass the fluid from the pump. Under such conditions it is apparent that check valve 145 will remain closed.

However, should the elevation data reverse, causing a reversal of pressure, check valve 145 will open, allowing fluid flow in the opposite direction corresponding to increase in the elevational position of the gun. As the gun is thus elevated, piston 139 is automatically removed from port 141 by the action of spring 143, and the normal conditions of operation of the system are restored. Limit stop 140' operates in exactly the same manner as limit stop 140 but becomes effective upon the gun reaching its upper limit in elevation.

Should the gun become jammed for any reason or should the transfer switch 180 be set to its manual position, it is apparent that the fluid pressure between pipes 107 will increase, since fluid flow will be prevented. In order to prevent this pressure from exceeding a predetermined safe limit under such conditions, the relief valves 111 and 111' are provided. These valves are set so that when the pressure between pipes 107 exceeds a desired limit, one or the other of these valves, depending on the direction of the pressure, opens, thus providing a direct channel between pipes 107, by-passing the rest of the system, and thus preventing the pressure from exceeding a predetermined limit.

Briefly reviewing the operation of the entire system, a synchronous transmission system is provided whereby an alternating potential signal is obtained across resistors 32 and 33 which corresponds to the angular disagreement between the gun 23 and the director shaft 10. Two direct current generators 70 and 80 are provided, one being driven in correspondence with the director shaft 10 and the other being driven in correspondence with the gun 23, whereby a direct current voltage signal proportional to the angular rate of rotation of director shaft 10 is obtained across resistor 31, and a direct current voltage signal proportional to the angular rate of rotation of gun 23 is obtained across resistor 38. A similar direct current generator 102 is provided in order to obtain a voltage across resistor 35 which is proportional to the angular acceleration of the gun 23, as will be explained hereinafter.

All of the above signals, comprising one alternating potential signal, and three direct poten-

tial signals are introduced into a balanced modulator 50 which combines them into one corresponding composite alternating potential signal which appears across output transformer 52. This output signal is then amplified in the balanced amplifier 53 and the output applied to one phase of a two-phase motor 55, the other phase of which is constantly energized from a suitable alternating current source. In this manner the motor 55 is caused to rotate at a speed and in a direction corresponding to the magnitude and phase of the composite alternating potential signal.

A Vickers hydraulic variable speed unit is provided consisting essentially of electric motor 67 driving a hydraulic pump 63, the fluid pressure generated by said pump driving the hydraulic motor 66 which directly actuates gun 23. The speed and direction of rotation of the hydraulic motor 66 and of the gun 23 may be controlled by the setting of a stroke rod 63 which in turn is directly connected to motor 65 and controlled thereby. In this manner the composite alternating potential signal controls the direction and the speed of rotation of gun 23.

Since the gun is rotated by the Vickers unit at an angular rate proportional to the setting of stroke rod 63, the rate of displacement of the stroke rod may be taken as a measure of the angular acceleration of the gun. Accordingly, direct current generator 102 is actuated in accordance with stroke rod 63, as by being directly connected to the same motor 55 as is the stroke rod. Thus, the voltage generated by generator 102 is proportional to the angular acceleration of the gun, and this generated voltage is applied across resistor 35 to supply that previously referred to component of the composite signal which is proportional to the angular acceleration of the gun.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described our invention, what we claim and desire to secure by Letters Patent is:

1. In a positional control system, a controlling object, a controlled object, means having a one-to-one relationship between said two objects producing an A. C. signal proportional to the positional displacement of said two objects and reversible in phase with the direction of said displacement, a second means having a multiple relationship between said two objects for producing a similar signal responsive to a smaller displacement in position between said two objects, said signals normally exercising joint control of said controlled object with said second signal preponderant, and means including a saturable reactor connected across said second signal for limiting the same to a predetermined amount, whereby, when the relative positions of the controlling and controlled objects exceed a predetermined angle, the first signal prevails and prevents loss of synchronism.

2. A positional control system as claimed in claim 1, having means for preventing 180° ambiguity of the first-named signal control, whereby complete self-synchronism is obtained.

3. In a system for positioning a heavy object

in correspondence with the position of a controller, means producing an alternating current signal proportional to positional displacement of the object and controller, servo means controlled by said signal for driving the object including a variable speed hydraulic gear having a variable displacement pump and a hydraulic motor driven therefrom, said gear having a control member moved in response to the sense and amplitude of said signal and governing, by its position, the speed of said servo means, and a generator connected to said member producing a variable direct current signal proportional to the acceleration of said gear for opposing said first signal and a modulator for combining said signals, the output of which controls said servo means.

4. In a positional control system, a controlling object, a controlled object to be kept in positional agreement with said controlling object, means for obtaining an alternating electric potential proportional to positional disagreement of said two objects and reversing in phase in correspondence with change of sign of said disagreement, means for obtaining unidirectional electric potentials respectively proportional to the velocities of said two objects, thermionic tube means jointly receiving said several potentials as an input and supplying a reversible phase alternating output proportional to the combination thereof, an alternating current source, and reversible driving means for said controlled object including a two-phase motor having one phase constantly excited from said source and a second phase receiving the reversible phase output of said thermionic means.

5. In an automatic system for positioning a rotatably mounted gun in positional correspondence with a remote controller, means for obtaining an electric potential measuring the positional disagreement of said gun and controller, means for rotating said gun including a variable speed hydraulic transmission having a positionable member determining the output speed thereof, means for obtaining an electrical potential proportional to the position of said member, means for deriving an electrical potential proportional to a combination of said first two potentials, and means actuated by said derived potential for positioning said member.

6. In a system for automatically positioning a rotatably mounted gun in positional agreement with the position of a remote controller, means for obtaining an electrical potential proportional to the positional disagreement of the gun and controller, means for rotating the gun including a variable speed hydraulic transmission having a positionable member determining the speed thereof, means for obtaining an electrical potential proportional to the position of said member, means driven from the gun for obtaining an electrical potential proportional to the velocity thereof, means for deriving from said three potentials a further potential proportional to a com-

bination thereof, and means actuated by said derived potential for positioning said member.

7. In a system for positioning an object in correspondence with the position of a remote controller, means producing a signal proportional to the positional disagreement of the object and controller, servo means controlled by said signal for driving the object including a variable speed hydraulic gear having a variable displacement pump and a hydraulic motor driven therefrom, said gear having a control member moved in response to the magnitude of said signal and governing, by its position, the speed of said motor, and means responsive to the pressure of the driving fluid for limiting or reversing the motion of said member at high speed positions to limit the power consumption.

8. In a system for positioning a gun in correspondence with the position of a remote controller, means producing a signal proportional to the positional disagreement of the gun and controller, servo means controlled by said signal for driving the gun including a variable speed hydraulic gear having a variable displacement pump and a hydraulic motor driven therefrom and operatively connected to the gun, and means for further controlling said driving means in accordance with the output pressure of said pump, said last means including means inversely responsive to the speed of rotation of the gun for adjusting the displacement of said pump to the power developed thereby.

9. In a system for positioning a rotatably mounted gun, a hydraulic variable speed gear driving said gun including a variable displacement pump with operating means therefor actuating a hydraulic motor operatively connected to the gun, displacement adjusting means limiting the increase of power delivered by said pump with increase of output pressure, said adjusting means having a plurality of degrees of response sequentially effective with increase of pressure, and a limit stop comprising means actuated by the gun at a predetermined position in the travel thereof for effectively blocking the circulation of operating fluid between said pump and motor, the output pressure of said pump being then modified by said limiting means.

10. In a gun positioning mechanism, a variable displacement hydraulic pump, driving means for said pump, a hydraulic motor connected for driving a gun and actuated in accordance with the displacement of said pump, means controlling the output power of said pump with increase of pressure according to a desired law of variation over a selected range, said controlling means being differently responsive to increase of pressure over selected portions within said selected range, and pressure relief means limiting increase of power beyond said range.
